UNITED STATES PATENT OFFICE.

NELSON ST. PETER, OF MOUNT VERNON, NEW YORK.

TOOL FOR REMOVING AND REPLACING MOTOR PARTS.

Application filed January 8, 1927. Serial No. 159,859.

The primary object of my invention is to provide a simple, convenient and effective device for removing and replacing the springs, valves and other parts of motors, particularly those of the valve-in-head Buick types and of many airplanes. In motors of this type, a spring depressed cam-actuated follower through a ball and socket or universal joint elevates one arm of a pivoted and rocking lever, the other arm of which lever depresses the valve stem and opens the valve against the pressure of a spring.

To remove the valve-raising spring and the valve for repairs or otherwise it is advisable first to lift the cam-actuated arm and depress the valve-operating arm of the lever against the stiff pressure of the valve spring, so as to permit the socket section of the universal joint to be removed from the cam follower, and thereby leave that arm of the lever free to be depressed, and therefore the valve-actuating arm of the lever to be raised to the fullest extent.

The valve-actuating arm being then raised out of the way, the valve spring and the valve can be removed from the valve housing in the usual way. Conveniently to effect this manipulation of the arms of the rocking-lever against the pressure of the spring, I employ a simple, effective and convenient tool consisting of a bar having a handle at one end, a bearing at the other end to bear upon the arm of the lever to be depressed, a hook depending from the bar midway of its length to engage the underside of the lever arm to be raised, the down bearing and hook being both offset laterally from but axially in lines substantially parallel with the line of the handle. Thus while the handle bar will pass to one side of the rocking lever, the down bearing and hook will both be in the vertical plane of and engage the rocking lever so that when the handle is raised, the hooked lever arm will be raised and the borne lever arm will be depressed for removing the valve spring and valve as above stated, the handle being in a line substantially parallel with the lines of the down bearing and hook, the handle can be raised without interfering with the usual raised cover over the rocking lever.

In order that my invention may be fully understood, I shall first describe in detail the

mode in which I at present prefer to carry the invention into practice and distinctly point out the invention in the claim.

Reference is to be had to the accompanying drawing forming part of this application in which corresponding parts are designated by the same numbers in the figures.

Figure 1 represents a tool embodying my invention applied to the valve operating rocking lever of a valve-in-head motor of the well-known Buick motor type.

Figure 2 is an enlarged perspective view of the tool.

Figures 3 and 4 are enlarged top and bottom views, respectively, of the tool.

In the drawings, 3 designates one of the valves of the Buick type motor illustrated; 4 designates the valve stem; 5 the valve raising spring; 6 the spring cap; 7 the rocking lever; 8 the pivoting boss thereof; 9 the cam-actuated follower; 10 the follower-depressing spring, and 11 the socket section and 12 the ball section of the universal joint connecting the rocking lever 7 with the cam-follower 9.

To engage and rock the lever 7 against the pressure of the valve spring, I form my improved tool of a rigid metal bar 13 having a handle 14 at one end, a bearing 15 on the other end preferably grooved on its underside to engage and embrace one arm of the lever 7, a rigid hook 16, spaced from bearing 15 and depending from the underside of the bar to engage and embrace the underside of the other arm of the lever 7 and by preference a lateral offset 17 between the hook 16 and bearing 15, so that while the handle bar will pass to one side of the lever 7, the down bearing 15 and hook 16 will lie in lines laterally offset from but substantially parallel with the line of the handle bar and in the vertical plane of the lever, and thus bring the line of pressure of the hook 16 and bearing 15, directly over the lever 7. The usual cover over the valves is raised on its hinge to give access to the lever 7, and the handle 14 is made as described substantially parallel with the lines of the bearing 15 and hook 16, so that it can be raised to the required extent without interfering with the cover.

The hook 16 of the tool being engaged as described with the cam-actuated arm of the lever and the bearing 15 with the valve-actu-

ated arm, the cam-actuated arm can be easily raised against the pressure of the valve spring to remove, if desired, the socket section 11, and free that arm of the lever. The 5 hook 16 of the tool being then engaged with the valve-operating arm of the lever 7 and the bearing 15 with the cam-actuated arm of the lever, the valve-operating arm can be easily raised for freeing and removing the 10 valve spring and valve 3, in the usual way.

By a similar convenient use of the tool the valve and spring can be replaced with the same ease and expedition.

It is evident that many changes may be 15 made in the details of my invention without departing from the boundaries thereof as defined by the following claim.

I claim as my invention:

A tool for manipulating a spring actuated rocking lever as described, consisting of 20 a rigid bar having a handle at one end, a bearing at the other end, to engage and press downward one lever arm, and a medial depending hook to engage and lift the opposite lever arm, the downwardly pressing bearing 25 and hook being offset laterally from the handle bar, but in lines substantially parallel with the line of the handle bar, so that while the handle bar lies to one side of the lever, the downwardly pressing bearing and hook will lie in the vertical plane of the 30 lever and engage the respective arms thereof.

In testimony whereof I affix my signature.

NELSON ST. PETER.
